UNITED STATES PATENT OFFICE

2,551,632

HOBBYHORSE

Edward H. Pichler, Snohomish, Wash.

Application October 1, 1948, Serial No. 52,338

7 Claims. (Cl. 272—53.1)

1

My invention relates to a hobbyhorse. More particularly, my invention relates to a device wherein the seat thereof moves in a circular path and thus simulates the galloping of a horse.

While my invention will be described in connection with a hobbyhorse, it is to be expressly understood that devices embodying my invention may have the appearance of many other animals and the term hobbyhorse as used herein and the general appearance of a horse illustrated in the drawings are to be understood as illustrative and not as limitations of my invention. Also it is to be expressly understood that my invention is not to be limited to toy or amusement devices for children but is to include exercising devices for adults.

In the prior art of hobbyhorses, it was common practice to provide a back and forth or longitudinal movement of the seat member but, as far as I am aware, the prior art devices did not provide for a movement of the seat member in a circular path. Thus much of the desired stimulating and exciting motions of riding horseback were absent when riding hobbyhorses.

It is thus a general object of my invention to provide a device wherein a rotary motion much like the galloping of a horse is obtained.

It is the further object of my invention to provide a device wherein a seat member is mounted on crank arm means and said seat member is movable toward and away from lever means on the same crank arm means, so that the seat can be moved by an operator by causing relative motion between the seat means and said lever means.

It is the further object of my invention to provide a seat means, a lever means relatively movable toward and away from said seat means, and operating lever means interconnecting the two and which operating lever means may be in the form and shape of the part of an animal such as the head of a horse.

It is the further object of my invention to provide spring means operatively disposed in the power assembly of a hobbyhorse so that the weight of a rider may be in effect balanced out and the entire applied motive power may be utilized to operate the hobbyhorse. In my invention, said spring means are preferably adjustable to take care of riders of different weights.

The above mentioned general objects of my invention, together with others inherent in same, are attained by the device illustrated in the accompanying drawings throughout which like reference numerals indicate like parts.

2

Figure 1 is an elevational view of a device embodying my invention;

Fig. 2 is an elevational view, on a smaller scale than Fig. 1, with the moving parts rotated substantially ninety degrees from their positions shown in Fig. 1;

Fig. 3 is a view similar to Fig. 2 and with the moving parts rotated ninety degrees from their positions shown in Fig. 2;

10 Fig. 4 is a view similar to Fig. 3 and with the moving parts rotated ninety degrees from their positions shown in Fig. 3;

Fig. 5 is a detached view in end elevation of the crank arm illustrated in the previous figures 15 and with the crank arm substantially in the same position as it is shown in Fig. 1;

Fig. 6 is an elevational view with the central portion of the crank arm broken away, and taken substantially in the direction of broken line 6—6 20 of Fig. 5; and

Fig. 7 is a plan view, with parts in section, taken substantially on broken line 7—7 of Fig. 2.

Referring more particularly to Figs. 1 and 7 of the drawings, a base frame means comprises

25 side slats 8, end frames 9, and four vertically disposed supports 10. The supports 10 are each provided with a bearing 11. Each bearing 11 rotatively supports a crank arm portion 12. The crank arm portions 12 of each of the two longitudinally spaced crank arms are connected to crank arm portions 13 at an angle of substantially ninety degrees. The crank arm portions 13 are connected with crank arm portions 14 and at angle of substantially ninety degrees. The

30 crank arm portions 14 are connected to crank arm portions 15. Each crank arm portion 15 lies in a plane which is substantially one hundred five degrees to the plane in which crank arm portions 13 lie. The crank arm portions 12—13 and 14 lie substantially in a common plane, such as a vertical plane as viewed in Fig. 1 of the drawings. The crank arm portions 15 of each crank arm are interconnected by crank arm portion 16. As viewed in Fig. 1 of the drawings, the crank arm portions 15 extend in substantially a horizontal plane, inwardly of the device and are interconnected by the crank arm portions 16. The crank arm portions 12—14 and 16 function as

35 bearings.

40 The seat assembly comprises a platform 17 on which a person may sit. Obviously a back rest as well as any suitable decorative effects may be employed. The platform 17 carries legs 18 which are provided with bearings 19. Bearings 19 rotatively support crank arm portions 14. An op-

45

50

55

erating lever 20 may have suitable decorative effect such as the head and neck of a horse. The head 20 preferably carries hand grasping means such as pins 21. The head 20 is pivoted to the platform 17 as by hinges 22. Stirrup means 23 provide suitable foot rests. Lever means 24 extend between the forward and rear crank arms 12-13-14-15-16. Each end portion of a lever means 24 is provided with bearings 25 which rotatively mount the crank arm portions 16. Adjustable spring means 26 interconnect between the rear portion of a lever 24 and a forward portion of the seat assembly.

In the drawings, I have indicated two springs 26 (see Fig. 7) but obviously a single spring can be substituted therefor. Similarly, I have indicated two lever means 24 and two connecting rods 32 but obviously a single lever means 24 and a single connecting rod 32 may be employed.

From the foregoing, it will be apparent that a base frame means may comprise side slats 8, end frames 9 and vertically disposed supports 10; that the crank arm portions 12 are rotatively supported by bearings 11 carried by the base frame means; that crank arm portions 14 and 16 are offset bearings and describe concentric circles of different diameters about 12 as a center; that lever means 24 interconnect the crank arms through one set of the offset bearings; that the platform 17 is supported by the other set of offset bearings; and that a pivoted lever, as head 20, functions as operating lever means.

This may be accomplished by connecting a spring (as viewed in Fig. 1) to a rear portion of a lever 24 and to a forward leg 18. A means to adjust the tension of spring 16 is indicated by a turnbuckle 27.

Connecting rod means 32 have the respective end portions thereof pivoted to the rear crank arm portion 16 and to a portion of the head 20 below the hinge 22.

Referring now more particularly to Fig. 1 of the drawings, the parts are shown in their normal and raised position. When a rider sits on a platform 17, the spring 26 is placed under tension and the platform descends by reason of such weight and moves toward the position of Fig. 2. The spring should be adjusted in accordance with the weight of a particular rider for maximum ease of operation. This adjustment should be such that it takes some pressure on the pins 21 to cause the platform 17 to fully descend as the springs 26 are being placed under tension and this tension is later utilized in causing the platform 17 and the rider to rise.

Referring to Fig. 2 of the drawings, the bearings 19 will move in a circular path indicated by circular broken line 28. Also the bearings 25 will move in a circular path indicated by the circular broken line 29. While the travel may be clockwise or counter-clockwise, depending upon the rest position of portions 13 (i. e. angled to the right or left of the vertical in Fig. 1) or the direction of the initial movement of the pins 21 (i. e. back or forth), in the drawings I have illustrated a cycle by the positions of the parts in Figs. 1 to 4 and have assumed that the direction of rotation of said forward bearings 19 and 25 will be in a clockwise direction.

Referring now to Fig. 3 of the drawings, the rear bearings 25 will rotate in a circular path indicated by broken line 30 and the rear bearings 19 will rotate in a circular path indicated by broken line 31.

Assuming the directions of rotation just described, a rider on platform 17 may permit the pins 21 to move rearwardly by reason of his or her weight and, upon rotation of ninety degrees, the parts will be in the position of Fig. 2 of the drawings and the upper portion of the lever 20 will be in its rearmost position of angular movement. Then upon application of forward motion, on the head 20 and in the direction indicated by the arrow in Fig. 2, the parts will be moved ninety degrees and in to the position indicated in Fig. 3 of the drawings. It is preferable that the springs 26 be adjusted so some pressure is required for movement during this portion of the cycle so the springs 26 will provide the necessary power so the platform 17 and the rider will be moved upwardly and at an increased rate of travel later in the cycle. This "snap" or increased rate of rise provides for a most enjoyable ride.

Upon further movement of the head forward, as indicated by the arrow in Fig. 3 of the drawings, the bearings 19 and 25 will pass through dead center and the head may then be urged rearwardly as indicated by the arrow above the head in Fig. 4 until the parts assume the position in Fig. 1 and thereafter the cycles can be continued by the weight of the rider and by oscillating the lever or head member 20.

Forward and rear crank arms 12-13-14-15 and 16 should be identical for ease and smoothness of operation. Also the bearings formed by crank arm portions 12-14 and 16 should be aligned and properly fit bearings 11-19 and 25. The levers 24 link the forward and rear cranks 12-13-14-15-16 together so they move in unison.

As it appears from the drawings, bearings 19 and 25 revolve about the same axis, namely, crank arm portion 12 but they follow circular paths of different diameters. Thus as the bearings 19 and 25 rotate, the levers 24 move relatively toward and away from the platform 17 and the crank portion 16 moves toward and away from a forward portion of the platform 17. The weight of the rider tends to move the platform 17 downwardly and relatively away from the levers 24. As springs 26 urge the levers 24 and the platform 17 toward each other, the springs 26 carry the load of the rider. Also when the device is moving from the position in Fig. 1 of the drawings, and to and through the position shown in Fig. 2 of the drawings, the platform 17 and the levers 24 are moving relatively away from each other. Thus as the platform 17 is moving downwardly, the tension on spring 26 is increasing and the weight of the rider is utilized in increasing the tension on spring 26. After the parts reach the positions indicated in Fig. 3, the platform 17 is in its lowest position and the platform starts to rise. The tension of the spring means 26 is thus utilized to lift the platform 17 and in turn the rider through the portion of the cycle commencing just after Fig. 3, through the position indicated in Fig. 4 and toward the position indicated in Fig. 1 of the drawings.

Obviously changes may be made in the forms, dimensions, and arrangement of the parts of my invention without departing from the principle thereof, the above setting forth only a preferred form of embodiment.

I claim:

1. A device to be ridden comprising base frame means; crank arm means rotatively supported by said base frame means and having offset bearings thereon revolving in two concentric circles; lever

means having a portion thereof rotatively mounted on one of said offset bearing means; a seat assembly having a portion thereof rotatively mounted on the other of said offset bearing means and relatively movable toward and away from said lever means; and operating lever means for moving said seat assembly and said first mentioned lever means toward and away from each other.

2. A device to be ridden comprising base frame means; crank arm means having a first bearing means rotatively supported by said base frame means and having second and third bearing surfaces revolvable about said first bearing means and describing, when in motion, circles of different diameters; lever means having a portion thereof rotatively mounted on said second bearing surface of said crank arm means; a seat member having a portion thereof rotatively mounted on said third bearing surface of said crank arm means and relatively movable toward and away from said lever means; and operating lever means for moving said seat assembly and said first mentioned lever means toward and away from each other.

3. A device to be ridden comprising base frame means having longitudinally spaced bearings thereon; a crank arm means having a first bearing means rotatively supported by each of said bearing means of said base frame means, each of said crank arm means having second and third bearing surfaces revolvable about the first bearing means thereof and describing, when in motion, circles of different diameters; lever means having the end portions thereof rotatively mounted on the second bearing surfaces of said two crank arm means; a seat member having longitudinally spaced bearings rotatively mounted on the third bearing surfaces of said two crank arm means; a pivoted arm carried by said seat member; and an interconnecting link having its end portions rotatively connected with said lever means and said pivoted arm.

4. A device to be ridden comprising base frame means having longitudinally spaced bearings thereon; a crank arm means having a first bearing means rotatively supported by each of said bearing means of said base frame means, each of said crank arm means having second and third bearing surfaces revolvable about the first bearing means thereof and describing, when in motion, circles of different diameters; lever means having the end portions thereof rotatively mounted on the second bearing surfaces of said two crank arm means; a seat member having longitudinally spaced bearings rotatively mounted on the third bearing surfaces of said two crank arm means; a pivoted arm carried by said seat member; an interconnecting link having its end portions rotatively connected with said lever means and said seat member; and resilient means urging said seat member and said lever means toward each other.

5. A device to be ridden comprising base frame means having longitudinally spaced bearings thereon; a crank arm means having a first bearing means rotatively supported by each of said bearing means of said base frame means, each of said crank arm means having second and third bearing surfaces revolvable about the first bearing means thereof and describing, when in motion, circles of different diameters; lever

means having the end portions thereof rotatively mounted on the second bearing surfaces of said two crank arm means; a seat member having longitudinally spaced bearings rotatively mounted on the third bearing surfaces of said two crank arm means; a head member pivoted at a mid portion thereof to said seat member; handle means carried by an upper portion of said head member; and an interconnecting link having its end portions rotatively connected with said first mentioned lever means and a lower end portion of said head member.

6. A device to be ridden comprising base frame means having longitudinally spaced bearings thereon; a crank arm means having a first bearing means rotatively supported by each of said bearing means of said base frame means, each of said crank arm means having second and third bearing surfaces revolvable about the first bearing means thereof and describing, when in motion, circles of different diameters; lever means having the end portions thereof rotatively mounted on the bearing surfaces of said two crank arm means which describe the larger circle; a seat member having longitudinally spaced bearings rotatively mounted on the bearing surfaces of said two crank arm means which describe the smaller circle; a pivoted arm carried by the said seat member; and an interconnecting link having its end portions rotatively connected with said lever means and said pivoted arm.

7. A device to be ridden comprising base frame means having a pair of laterally spaced bearings and a second pair of laterally spaced bearings longitudinally spaced from the first pair of laterally spaced bearings; a crank arm means having a first bearing means rotatively supported by each of said pair of laterally spaced bearing means, each of said crank arm means having second and third bearing surfaces revolvable about the first bearing means thereof and described, when in motion, circles of different diameters; lever means having the end portions thereof rotatively mounted on the second bearing surfaces of said two crank arm means; a seat member having leg members thereon, and said leg members having longitudinally spaced bearings rotatively mounted on the third bearing surfaces of said two crank arm means; and operating lever means having its mid portion pivotally connected to said seat member; handle means carried by an upper portion of said operating lever means; and an interconnecting link having its end portions rotatively connected with a lower portion of said operating lever means and with said first mentioned lever means.

EDWARD H. PICHLER.
